US00D621017S

(12) **United States Design Patent**
Quinn et al.

(10) **Patent No.:** US D621,017 S
(45) **Date of Patent:** ** Aug. 3, 2010

(54) **AIR DRYER**

(75) Inventors: **Leonard A. Quinn**, Lagrange, OH (US);
Gregory Ashley, Amherst, OH (US)

(73) Assignee: **Bendix Commercial Vehicle Systems LLC**, Elyria, OH (US)

(**) Term: **14 Years**

(21) Appl. No.: **29/345,914**

(22) Filed: **Oct. 23, 2009**

(57) **CLAIM**

We claim the ornamental design for an air dryer, as shown and described.

DESCRIPTION

FIG. 1 is a perspective view of an air dryer that is a first embodiment of the new design;

FIG. 2 is a first side view of the air dryer of FIG. 1;

FIG. 3 is a second side view of the air dryer of FIG. 1;

FIG. 4 is a third side view of the air dryer of FIG. 1;

FIG. 5 is a fourth view of the air dryer of FIG. 1;

FIG. 6 is a top view of the air dryer of FIG. 1; and,

FIG. 7 is a bottom view of the air dryer of FIG. 1.

The portions of the Figures shown in phantom lines are not part of the claimed design and are for illustration only.
